(**) Term: **14 Years****(57) CLAIM**(21) Appl. No.: **29/426,665**

The ornamental design for a telescopic extension with a scraper and a removal head, as shown and described.

(22) Filed: **Jul. 9, 2012****DESCRIPTION**(51) **LOC (10) Cl.** **04-01**

FIG. 1 is a first-side elevation view of a telescopic extension with a scraper and a removal head;

(52) **U.S. Cl.**

FIG. 2 is a second-side elevation view of the telescopic extension with the scraper and the removal head;

USPC **D32/50**; D32/51

FIG. 3 is a third-side elevation view of the telescopic extension with the scraper and the removal head;

(58) **Field of Classification Search**

FIG. 4 is a fourth-side elevation view of the telescopic extension with the scraper and the removal head;

USPC D32/40-45, 50-52, 49; 15/118, 244.1,

FIG. 5 is an elevation view of the telescopic extension with the scraper and the removal head illustrating a first side of the removal head;

15/244.2, 244.3, 244.4, 116.1, 116.2,

FIG. 6 is an elevation view of the telescopic extension with the scraper and the removal head illustrating a second side of the removal head;

15/119.1, 119.2, 104.9, 228, 229.2, 229.4;

FIG. 7 is a first perspective view of the telescopic extension with the scraper and the removal head illustrating the first side of the removal head;

401/135-140

FIG. 8 is a second perspective view of the telescopic extension with the scraper and the removal head illustrating the second side of the removal head; and,

See application file for complete search history.

FIG. 9 is a perspective view of the telescopic extension with the scraper and the removal head illustrating the telescopic extension coupled along a length of the telescopic extension to the first side of the removal head.

(56) **References Cited**

The broken line showings of protrusions, apertures, and other features on the scraper and the removal head are for illustrative purposes only and form no part of the claimed design.
